WEAR ADAPTER FOR DRILL PIPES

Jackson G. Hinkle, Carmi, Ill.

Application July 30, 1951, Serial No. 239,223

5 Claims. (Cl. 255—28)

1

This invention relates to new and useful improvements in drill pipe used in the drilling of oil and gas wells. The principal object of the invention is to eliminate a substantial portion of the wear on the drill pipe, this being accomplished by the provision of adapters which are installed in the drill pipe and which are relatively greater in diameter than the pipe itself, so that the adapters themselves absorb wear and the pipe does not sustain weakening.

In various sections of the United States a large number of drill collars are utilized to add more weight on the drilling bit. This invention eliminates the need for an excessive number of such collars. In other sections of the United States only one or two drill collars are used, but weight is applied to the drilling bit by allowing the weight of the drill pipe to rest upon the same. This condition is undesirable for two reasons, namely, the portion of the drill pipe below the equalizing joint is constantly whipping and rubbing against the walls of the hole thereby putting excessive wear on the pipe by abrasion. Furthermore, the wobbling and lashing motion of the drill pipe tends to affect the straightness of the hole being drilled. The instant invention tends to stiffen the pipe by reducing the distance between the tool joints, as well as reducing the distance between the walls of the hole and the outside surface of the drilling string, whereby weight is forced in a more straight downward thrust and side thrust is considerably reduced.

With the above and other objects in view, this invention resides mainly in the construction and arrangement of parts as shown in the accompanying drawings, in which:

Figure 1 is an elevational view of a drill pipe with tool joints and wear adapters, installed in a well, the latter being shown in section;

Figure 2 is an enlarged fragmentary view of the assembled wear adapter;

Figure 3 is a longitudinal sectional view of the assembled adapter;

Figure 4 is an elevational view of a spring used in the adapter; and,

Figure 5 is an elevational view of the spring applied to the drill pipe.

Like characters of reference are used to designate like parts in the specification and the accompanying drawings.

Referring to the drawings in detail, the numeral 10 designates sections of drill pipe connected together by conventional tool joints 12, 14. Ordinarily, when weight is applied to the drill pipe, rotating motion causes the drill pipe to be

2

whipped or lashed against the inner wall of the well hole 16, which causes considerable wear on the drill pipe so that after a period of time the weakened drill pipe must be discarded.

5 The instant invention eliminates a considerable amount of this wear by providing wear adapters 18 at longitudinally spaced points on the drill pipe, so that the adapters rather than the pipe rub against the wall of the hole 16.

10 Each of the adapters 18 comprises a tubular sleeve consisting of a pair of half sections 20, 22 which have scalloped adjacent edges 24. When the sleeve sections are applied to the pipe, a space exists between the edges 24, which space is 15 filled with welding material 26 to secure the two half sections together. The essence of novelty of this invention resides in the means for securing the adapter 18 to the drill pipe 10, this involving the provision of a helical spring 28, formed from flat stock and provided on its inner surface with gripping teeth 30. The inside diameter of the spring is somewhat smaller than the outside diameter of the drill pipe, so that when the spring is applied to the pipe, it is frictionally and firmly sustained thereon. A thin gasket of fiber material 32 is wound between the coils of the spring 28 around the drill pipe 10, which tends to absorb shock. The half sections 20, 22, provided inside thereof with complementary helical grooves 34 to receive the spring, are then installed in position on the pipe and welded together as already explained.

15 It will be noted that the adapters are so constructed that the installation or removal thereof, at the end of their useful life, is an extremely simple operation, which may be made on the site of operation so that no time is lost in moving the drill pipe and adapters to a machine shop for repair.

20 It is to be also noted that although prior to this invention other means have been tried in which the saving of wear on the drill pipe was the object, such means generally failed for the reason that fastening the adapter by welding to the pipe was an impractical necessity. Comparatively, in the instant invention welding material does not come in contact with the drill pipe.

25 While in the foregoing there has been shown and described the preferred embodiment of this invention it is to be understood that minor changes in the details of construction, combination and arrangement of parts may be resorted to without departing from the spirit and scope 30 of the invention as claimed.

Having described the invention, what is claimed as new is:

1. The combination of a drill pipe and a wear adapter comprising a resilient helical spring positioned on and frictionally engaging said pipe, a helical gasket provided on the pipe between the convolutions of said spring, and a wear sleeve comprising a pair of complementary sections embracing the pipe and the spring, said sections having complementary helical spring receiving grooves therein, and means rigidly securing said sections together.

2. A wear adapter for drill pipe comprising a sleeve consisting of a pair of complementary sections adapted to be rigidly secured together provided therein with a helical groove, and a resilient helical drill pipe engaging member positioned in said groove, and drill pipe gripping teeth on the inner surface of said member.

3. A wear adapter for drill pipes comprising a sleeve consisting of a pair of complementary sections, each of said sections having aligned helical grooves, and a resilient helical drill pipe engaging member of less inner diameter when unflexed than the outer diameter of the drill pipe with which it is adapted to be used, said member being received in said grooves.

4. A wear adapter for drill pipes comprising a sleeve consisting of a pair of complementary sections, each of said sections having aligned helical grooves, and a resilient helical drill pipe engaging member of less inner diameter when

unflexed than the outer diameter of the drill pipe with which it is adapted to be used, said member being received in said grooves, said member being provided with drill pipe gripping teeth on the inner surface thereof to provide frictional means for securing said wear adapter to a drill pipe.

5. A wear adapter for drill pipes comprising a sleeve consisting of a pair of complementary sections, each of said sections having aligned helical grooves, and a resilient helical drill pipe engaging member of less inner diameter when unflexed than the outer diameter of the drill pipe with which it is adapted to be used, said member being received in said grooves, said member being provided with drill pipe gripping teeth on the inner surface thereof to provide frictional means for securing said wear adapter to a drill pipe, each of said sections being provided with scalloped adjacent edges, and weld material between said edges securing said sections together.

JACKSON G. HINKLE.
